UNITED STATES PATENT OFFICE.

WILLARD B. FEATHERSTONE, OF WASHINGTON, DISTRICT OF COLUMBIA.

CONCRETE BUILDING.

1,124,404.

Specification of Letters Patent.

Patented Jan. 12, 1915.

Application filed July 2, 1909, Serial No. 505,695. Renewed June 8, 1914. Serial No. 843,910.

To all whom it may concern:

Be it known that I, WILLARD B. FEATHERSTONE, a citizen of the United States, residing at Washington, in the District of Columbia, have invented certain new and useful Improvements in Concrete Buildings, of which the following is a specification.

My invention relates to the use of concrete timbers of various shapes and sizes in place of wooden timbers or structural steel, and has for its object to produce strong durable fire-proof buildings at much less expense than is the case where brick or cement blocks etc. are used. I accomplish this by manufacturing in the shop by special machinery and appliances, the novel pieces of reinforced concrete which I call "concrete lumber," and placing them as described in this specification and shown in the drawings, in which—

Figure 1 is a sectional view of a portion of my new building. Figs. 2 and 3 illustrate parts of the roof. Figs. 4 and 5 show the top portion of a piece of concrete studding. Fig. 6 shows an H-beam as used between the first and second stories. Fig. 7 is a sectional view of the ridge-pole. Fig. 8 is a horizontal section through X X, Fig. 9. Fig. 9 is an elevation in part of the inner face of the wall shown in Fig. 8. Fig. 10 is a vertical section through Y Y, Fig. 8. Fig. 10^A shows an end of one of the T-studs of Fig. 8. Fig. 11 is a perspective view of a part of the wall near the second floor. Fig. 12 shows a T-beam reinforced in the web with a steel rod. Fig. 13 shows how a wall is held true during construction.

A, Fig. 1, is a piece of T-shaped studding, which rests in fresh concrete in the trough E³, which in turn rests upon the foundation wall F³. A' is another piece of T-shaped studding forming a portion of the inner surface, as A forms a portion of the outer surface of the wall. After a series of these inner and outer studs has been placed in position, they are temporarily adjusted, one good way being shown in Fig. 13 in which the nails R are driven through the plugs P into the nailing strips H'. This is shown in perspective in Fig. 11. The H-beam E, Figs. 1, 6, 10 and 11 is now placed over the top ends of the T-studs A, A', after the trough formed by the projections T (shown more clearly in Figs. 10, 10^A and 11), has been filled with fresh concrete in which the horizontal reinforcement U may be em-

bedded. The upper part of the H-beam E may now be filled with concrete mortar, and similar T-studs put in place for the second story, after which the modified H-beam E', Fig. 1, is adjusted and the trough filled with concrete mortar preparatory to receiving the roof timber C, Fig. 1.

The floors of my new building are constructed of T-beams either erect as B' or inverted as B, Fig. 1. The opposite walls of the house are conveniently tied together by rods G⁶, protected by concrete G⁵, the ends of the rods being preferably embedded in the fresh concrete in the horizontal bonding members such E and E'.

The ridge-pole F, Figs. 1 and 7, may be made of concrete or any other suitable material and is preferably stiffened by wires or rods F², which are engulfed by the fresh concrete after slipping into grooves or notches in the ends of the roof members similar to S, Fig. 5. The H-beam E, Fig. 6, may also have wires or rods E² designed to engage the slcts S, Fig. 5, in the ends of the T-studs. The object of this arrangement is to provide protection from the elements for the wires E² by completely surrounding them with concrete.

The roof timbers C may be shaped and arranged as shown in Fig. 2, the webs Q being reinforced and designed to stiffen the flanges C. The lip C' along one edge of the flange is designed to engage the inverted lip C² on the opposite edge of the flange of the adjoining timber. In Fig. 3 the lips C³ are elevated on both edges of the flange and are covered by a sort of secondary ridging F', F''. The junction of roof timbers of either type C or C' may of course be cemented with suitable material, preferably an elastic weather-proof composition. The bosses or projections D, Figs. 1, 4 and 5 are for the purpose of stiffening the T-studs A' where they assist in supporting the floor beams B. Similar projections D' upon the basement girder D⁴, Fig. 1, are for the purpose of giving increased support to the floor beams B'.

I claim:

1. A building having walls constructed of two rows of vertical concrete timbers of approximate T-shape and having webs and flanges, the timbers being placed back to back, said timbers having on the interior faces thereof, projections forming shelves adjacent the upper ends, the shelves corre-

sponding in length with the width of the flanges and in width approximately half the timber web width, said shelves of adjacent juxtaposed timbers jointly forming a trough 5 and reinforced concrete in the trough.

2. A building having walls constructed of two rows of vertical concrete timbers of approximately T-shape, and having webs and flanges, the timbers being placed back to back, nailing strips along the vertical edges 10 of the webs, inwardly projecting nailing plugs near the vertical edges of the flanges, for the purpose of facilitating alinement by means of nails or the like driven through 15 the plugs of one row of timbers into the strips of the other row.

3. A building having walls constructed of two rows of vertical, oppositely placed, parallel concrete timbers of approximately T- 20 shaped section, having nailing strips H' , H'' , at the corners of the webs and nailing plugs P , P' , P'' near the edges of the flanges, for the purpose of facilitating alinement by 25 means of nails or the like connecting the plugs and the strips, the points of said plugs projecting from the inner surface of the concrete to prevent full contact of the timbers.

4. A hollow wall constructed of two rows 30 of vertical concrete timbers of approximately T-shaped section having nailing strips on the corners of the webs and nailing plugs near the edges of the flanges, and so placed that the plugs in the flanges of one 35 row are adjacent to the strips on the webs of

the other row, the plugs projecting slightly to lessen the contact between the two rows.

5. A building block having longitudinally extending edges on opposite sides thereof, nailing strips secured to the block along the 40 longitudinal edges whereby when the blocks are assembled, the nailing strip on one side of a block lies in abutting relation to a strip on an adjacent block whereby the blocks can be secured together through said strips. 45

6. A building block of angular formation presenting longitudinally extending edges on opposite sides thereof, nailing strips secured to the block along the longitudinal edges whereby when the blocks are assembled the nailing strip on one side of a block lies in abutting relation to a strip of an adjacent block whereby the blocks can be secured together through said strips. 50

7. A building block of plastic material 55 comprising a web having flanges projecting therefrom, the web and flanges providing longitudinally extending edges, nailing strips secured along the edges of the web and flanges respectively, the nailing strips of a 60 flange of one block being in abutting relation with a strip of the web of an adjacent block when the blocks are assembled to form a wall or floor whereby adjacent blocks can be united through said strips.

WILLARD B. FEATHERSTONE.
